(57) **CLAIM**

The ornamental design for a mobile battery, as shown and described.

DESCRIPTION

FIG. 1 is a top, front, and right side perspective view of a mobile battery design of an embodiment of the present disclosure;

FIG. 2 is a bottom, back, and left side perspective view thereof;

FIG. 3 is a bottom, front, and left side perspective view thereof;

FIG. 4 is a top view thereof;

FIG. 5 is a bottom view thereof;

FIG. 6 is a right side elevational view thereof;

FIG. 7 is a left side elevational view thereof;

FIG. 8 is a front elevational view thereof; and,

FIG. 9 is a back elevational view thereof.

The broken lines shown in the drawings are for the purpose of illustrating portions of the mobile battery that form no part of the claimed design.
